CLAIM

The ornamental design for a bicycle rim with surface indicia, as shown and described.

DESCRIPTION

FIG. 1 is a top plan view of a bicycle rim with surface indicia;

FIG. 2 is an isometric view of a front and right side of a bicycle rim, to which the surface indicia of FIG. 1 is applied; and,

FIG. 3 is an isometric view of a rear and left side of the bicycle rim of FIG. 2.

It is understood that the surface indicia repeats around the circumference of the bicycle rim. The broken lines are included for the purpose of illustrating portions of the bicycle rim that form no part of the claimed design. The dash-dot-dash lines are included for the purpose of illustrating boundary lines and form no part of the claimed design.
